UNITED STATES PATENT OFFICE.

CHESTER D. AINSWORTH, OF WOLLASTON, MASSACHUSETTS, ASSIGNOR, BY MESNE ASSIGNMENTS, TO CONDIT ELECTRICAL MANUFACTURING CORPORATION, OF BOSTON, MASSACHUSETTS, A CORPORATION OF MASSACHUSETTS.

ELECTRIC SWITCH.

Application filed February 9, 1922. Serial No. 535,220.

To all whom it may concern:

Be it known that I, CHESTER D. AINSWORTH, a citizen of the United States, residing at Wollaston, in the county of Norfolk and State of Massachusetts, have invented an Improvement in Electric Switches, of which the following is a specification.

This invention relates to oil immersed electric switches.

Due to the electro-magnetic stresses acting upon the conducting components of an electric switch by current of a relatively high value, under certain conditions, the relatively movable conducting components may be forced away from firm electrical contact with each other and arcing may take place therebetween, and, consequently, the capacity of the switch may be reduced.

An object of this invention is to provide an electric switch with an improved form and arrangement of movable and stationary switch members and especially movable and stationary contact or arcing members by which the magnetic effect of the current carried by them acts to improve the electrical engagement of the co-acting contact members.

A further object is generally to improve the operation and construction of an electric switch.

Certain features of this invention are disclosed in my co-pending applications Serial No. 522,228, filed December 14, 1921, Serial No. 522,227, filed December 14, 1921, and Serial No. 585,672, filed September 1, 1922.

Fig. 1 is a side elevation of a switch embodying my invention with the side wall of the casing broken away to show the stationary and movable switch members.

Fig. 2 is a longitudinal sectional detail, in elevation, of the switch of Fig. 1 illustrating the switch-open position of the switch members.

Fig. 3 is a plan detail of the movable switch member.

Fig. 4 is a sectional view of the movable switch member along line 4-4 of Fig. 3.

Fig. 5 is a side view of the auxiliary contact members in switch-open position.

Fig. 6 is a similar view of the auxiliary contact members in switch closed position.

I have herein illustrated my invention as incorporated in an oil immersed electric

switch of the "up-break" type; yet the invention is not limited to such a type of switch.

As here shown, the electric switch includes a casing comprising the oil receptacle 10 and the switch frame 11. Said switch frame comprises a cover for the oil receptacle and is secured to the top of said receptacle by suitable means as the bolts 12. Stationary switch members 13 are carried by said switch frame and depend into the oil in the receptacle. The movable switch member has its switch rod 14 pivotally secured to and dependent from the pivoted arm 15 of the switch operating mechanism. Said mechanism is contained within the switch frame and includes an operating shaft 16 which is journalled in and extends through the opposite side walls of the switch frame. An arm 17 is secured to an outer end of said shaft externally of the casing and is connected by means of the rod 18 to the electrically controlled switch-actuating mechanism 19 secured externally to the switch frame. A spring 20 is in engagement with the arm 17 of the operating mechanism and serves to raise the movable switch member to switch-open position and is adapted to be compressed by the switch-actuating mechanism 19 in moving the movable switch member to switch-closed position. Stationary switch members 13 are carried by said switch frame 11 and terminate, within the casing, in the inwardly directed contact plates 21, the upper faces of which are adapted to be engaged by the bridging or brush member of the movable switch member in the usual manner.

My invention resides more particularly in the construction and arrangement of the auxiliary contact or arcing members by which the circuit through the switch is finally interrupted. The stationary auxiliary contact member structure includes supporting members 22 which are secured removably, as by the bolts 22^a, to the under side of the contact plates 21 and connected electrically therewith. Said supporting members extend laterally on opposite sides of said contact plates and the extended ends thereof are reflexed downwardly and outwardly as is illustrated more clearly in Figs. 5 and 6. The stationary auxiliary contact members comprise the substantially inflex-

ible plates 23 which are secured removably by suitable means, as the bolts 24, to the reflexed ends of said supporting members; and said contact members extend upwardly 5 and inwardly and terminate a substantial distance above and to the opposite sides of said contact plates 21. The upper ends 23^a of said plates are reflexed inwardly to form arcing tips from which the arc is struck 10 while the body portion of the plates are adapted to be engaged by the movable auxiliary contact members and carry the current temporarily.

The movable switch member includes the 15 switch rod 14 heretofore mentioned, and said rod carries at its lower end the movable current carrying and auxiliary contact members. The main current carrying member includes the bridging member comprising 20 the inverted brush member 25 which is secured to the lower face of a channel member 26 having the lateral upstanding ears 27. The lower end of the switch rod 14 is disposed between said ears and a pivot pin 28 25 is passed through said switch rod and ears whereby to connect the brush member pivotally with the switch rod. The brush member is adapted to engage the upper faces of the stationary contact plates 21 and carry 30 the current in the usual manner.

The movable auxiliary contact structure includes the supporting members 30 which are secured to the outer faces of said upstanding ears 27. The intermediate portions 33^a of said members on opposite sides of the ears 27 of the channel member 26 are reflexed outwardly and are then again reflexed to provide end portions 33^b which are disposed in parallel relation with each other. 40

Movable auxiliary contact members including the downwardly extended resilient strips 31 are secured by suitable means as the bolts 32 to the end-portions 33^b of said supporting members 30. Contact or arcing members 33 are secured removably by suitable means as the bolts 34 to the lower ends of said flexible strips 31. Bracing members 36 are extended between the pairs of contact members on opposite sides of the brush member and are secured to the ends 30^b of the supporting members 30 by the bolts 32. Tie-members 35 are extended between the contact members on the same side of the brush member and are also secured to said contact member 30 by the bolts 32.

This arrangement provides a rigid and strong supporting structure by which the movable contact members 31 are secured rigidly and connected electrically. It will 60 be noted that all members of the supporting structure are arranged edgewise with regard to the direction of motion of the movable switch member whereby but a small surface is presented to the oil to oppose the movement of the movable switch member and con-

sequently the switch member may move rapidly into open position.

The arrangement of the stationary auxiliary contact members 23 and the movable auxiliary contact members 31 is such that 70 the movable contact members engage the stationary contact members at the tips 23^a thereof and upon a continued movement of the movable switch toward switch closed position, the movable contact members 31 are flexed outwardly while being moved downwardly along and in contact with the outer face of said stationary contact members 23 whereby a long wiping action and 75 good electrical contact is obtained. The stationary contact members extend a substantial distance above the stationary contact plates 21 of the stationary switch members so that the movable switch member may be accelerated and have a rapid motion when 80 the auxiliary movable and stationary contact members finally separate and as a result, the arc will be rapidly drawn out and 85 quenched.

At that part of the movement of the 90 switch wherein the stationary and movable contact members are in engagement but the brush members are free from engagement with the stationary switch members, the current between the switch members will be 95 divided into two parallel paths including the auxiliary contact members on both sides of the switch members and this arrangement constitutes an important part of the invention. 100

By reason of the parallel arrangement of the auxiliary contact members above set forth and the parallel division of current in said contact members, with the current flowing in the same direction in adjacent contact members, the magnetic effect of the parallel currents is such as to inter-react and tend to draw the movable resilient contact members 31 inwardly toward each other and thereby 105 into increased firm and secure contact with the co-acting stationary auxiliary contact members whereby to insure good electrical engagement between the auxiliary stationary and movable contact members regardless of 110 the value of the current carried by them. 115

The arrangement of the auxiliary contact members at the sides of the stationary switch members is also advantageous in that gas can rise freely from the contact members and oil can flow freely about the contact members without substantial obstruction whereby to facilitate the quenching of the arc and the cooling of the auxiliary contact members. 120

It is obvious that the invention may be embodied in modified structures without departing from the spirit thereof. 125

I claim:

1. An electric switch having two relatively movable switch members each formed 130

with a main current-carrying member and two arcing members disposed on opposite sides of and extended in a circuit-opening direction beyond the contact face of and electrically connected with said main current-carrying member, and said switch members arranged to be moved to cause the engagement of their respective main current-carrying members and arcing members.

2. An electric switch having two relatively movable switch members each formed with a main current-carrying member and two arcing members disposed on opposite sides of and extended in a circuit-opening direction beyond the contact face of and electrically connected with said main current-carrying member, and said switch members arranged to be moved to cause the engagement of their respective main current-carrying member and arcing members, and means to pass the current in the same direction through the arcing members of the switch members.

3. An electric switch having a main current-carrying member, and two relatively flexible arcing members secured to and disposed on opposite sides of said main current-carrying member, and a movable switch member including a bridging-member arranged to engage said main current-carrying member, and two electrically-connected arcing members disposed on opposite sides of said bridging member and movable therewith into engagement with the aforesaid flexible arcing members.

4. In an electric switch, an auxiliary stationary and a cooperating auxiliary movable-contact member, both arranged substantially in line, and said movable contact member arranged to engage said stationary contact member substantially at the upper end thereof and move from the upper end toward the other end while in engagement with the face thereof and while preserving substantially its initial area of contact with said stationary contact member and have a final engagement with said stationary contact member a substantial distance away from the upper end thereof and with substantially its initial area of contact therewith and a main contact member associated with and disposed remote from the free end of each auxiliary contact member.

5. In an electric switch, a movable switch-member comprising a supporting structure, four arcing members arranged in sets of two at the opposite ends of said supporting structure, and a main bridging member carried by said supporting structure and having its opposite contact-ends disposed between the arcing members of the opposed sets.

6. In an electric switch, a movable switch-

member comprising a supporting structure, four arcing members all connected in parallel and arranged in sets of two at the opposite ends of said supporting structure, and a main bridging member carried by 70 said supporting structure and having its opposite contact-ends disposed between the arcing members of the opposed sets.

7. In an electric switch, a switch member including a contact plate, a supporting member secured to said plate having lateral downwardly and outwardly directed opposed end-portions extended on opposite sides of said contact plate, and contact members secured to said end-portions and 80 extended upwardly and inwardly above said contact plate.

8. In an electric switch, a stationary switch member including a contact plate, 85 a supporting member secured to said plate having lateral downwardly and outwardly directed end-portions extended on opposite sides of said contact plate, and contact members comprising flat strips secured to said end-portions and extended upwardly 90 and inwardly above and on opposite sides of the contact face of said contact plate.

9. In an electric switch, a stationary switch member including a contact plate, a supporting member secured to said plate 95 having lateral downwardly and outwardly directed end-portions extended on opposite sides of said contact plate, and contact members comprising flat strips secured 100 removably at their lower ends to said end-portions and extended upwardly and inwardly above and on opposite sides of the contact face of said contact plate.

10. In an electric switch, a stationary switch member having a main contact face and two detachable auxiliary contact members disposed on opposite sides of and angularly inclined with respect to said main contact face, and a movable switch member having a main contact member arranged to engage said main contact face, and two detachable auxiliary contact members disposed on opposite sides of said main contact member arranged to engage the auxiliary contact members of said stationary switch member.

11. In an electric oil switch, a movable switch member comprising a switch rod, a supporting structure secured thereto comprising a plurality of spaced flat members arranged with their edges directed in the path of movement of said switch member, auxiliary contact members carried by said supporting structure and a main current-carrying member disposed between said spaced flat members.

12. An electric switch having a movable switch member comprising a supporting structure, a bridging member disposed within the ends of said supporting structure and 130 extended lengthwise thereof, and two elec-

- trically-connected arcing members carried by each end of said supporting structure on opposite sides of and extended beyond the ends of said bridging member.
- 5 13. An electric switch having a movable switch member comprising a supporting rod, a supporting structure connected with the lower end of said rod, said supporting structure including two substantially parallel and spaced bars extended laterally in both directions from said rod, and two arcing members extended in the direction of movement of the switch member and secured in spaced relation at each end of said supporting structure.
- 10 14. An electric switch having a movable switch member comprising a supporting rod, a supporting structure connected with the lower end of said rod, said supporting structure including two substantially parallel and spaced bars extended laterally in both directions from said rod, and two arcing members extended in the direction of movement of the switch member and secured in spaced relation at each end of said supporting structure and a main bridging member carried by said structure between said contact members.
- 15 15. An electric switch having a movable switch member including a rectangular supporting frame comprising spaced side plates, end connecting and separating plates, arcing members depending from the corners of said frame, and a bridging member disposed within said frame and arcing members. 35
- 20 16. An electric switch having a movable switch member including a rectangular frame comprising connected and spaced end and side plates, arcing members carried by the connections between said end and side plates, and a main bridging member carried by said frame between said arcing members. 40
- 25 17. An electric switch having a movable switch member including a rectangular frame comprising connected and spaced end and side plates, arcing members carried by the connections between said end and side plates, supporting plates extended within said frame from the corners thereof, and a switch rod secured to said supporting plates. 45
- 30 18. An electric switch having a movable switch member including a rectangular frame comprising connected and spaced end and side plates, arcing members carried by the connections between said end and side plates, supporting plates extended within said frame from the corners thereof, a switch rod secured to said supporting plates and a main bridging member carried by said supporting plates and disposed within said arcing members. 55
- In testimony whereof, I have signed my name to this specification.
- CHESTER D. AINSWORTH. 60
